UNITED STATES PATENT OFFICE.

JOSEPH B. LONG, OF CHICAGO, ILLINOIS.

DESIGN FOR A CADDY.

SPECIFICATION forming part of Design No. 33,804, dated December 25, 1900.

Application filed August 20, 1900. Serial No. 27,507. Term of patent 3½ years.

To all whom it may concern:

Be it known that I, JOSEPH B. LONG, a citizen of the United States, residing at Chicago, in the county of Cook and State of Illinois, have invented and produced a new and original Design for Caddies, of which the following is a specification, reference being had to the accompanying drawings, which are made a part of this specification, and in which—

10 Figure 1 is a perspective view of a caddy embodying the new design. Fig. 2 is an end elevation thereof.

15 A caddy of the new design has a body the back and end walls of which are flat and vertical, while its front wall comprises a central panel C, the outer surface of which is curved in vertical planes, and two rectangular panels C' C', the outer surfaces of which are flat, flanking the panel C at its ends, the three 20 panels C C' being surmounted by a narrow raised strip or rib D, extending from end to end of the body and having along its horizontal margins inturned flanges d. The top of the caddy comprises a narrow flat portion 25 E, disposed horizontally, and a flat lid F, both extending from end to end of the body, which

lid inclines downward and forward, the ends G being correspondingly inclined. The body is supported by legs H at its four corners.

The leading essential feature of the new 30 design is the body, having its front divided into a panel C, the outer surface of which is curved in vertical planes and the panels C' flanking the panel C at its ends and having flat outer surfaces. 35

Minor features of the design are the narrow raised rib D, extending from end to end of the body along the upper margins of the curved panel C and flat panels C', and the legs at the four corners of a body having the 40 general shape and configuration above described.

What I claim as new, and desire to secure by Letters Patent, is—

The design for a caddy substantially as 45 herein shown and described.

Signed at Chicago, Illinois, this 30th day of July, 1900.

JOSEPH B. LONG.
